UNITED STATES PATENT OFFICE.

FRANCIES E. ELDREDGE, OF WAVERLY, IOWA.

GATE.

1,032,592.

Specification of Letters Patent.

Patented July 16, 1912.

Application filed June 8, 1911. Serial No. 631,939.

To all whom it may concern:

Be it known that I, FRANCIES E. ELDREDGE, a citizen of the United States, residing at Waverly, in the county of Bremer 5 and State of Iowa, have invented certain new and useful Improvements in Gates; and I do declare the following to be a full, clear, and exact description of the invention, such as will enable others skilled in the art to 10 which it appertains to make and use the same.

This invention relates to improvements in gates.

One object of the invention is to improve 15 the construction of the gate shown in United States Patent #883,182, granted to me March 31, 1908 whereby a lighter, simpler, stronger and more durable gate is provided.

With this and other objects in view, the 20 invention consists of certain novel features of construction, combination and arrangement of parts as will be more fully described and particularly pointed out in the appended claims.

25 In the accompanying drawings:—Figure 1 is a side view of one form of my improved gate; Fig. 2 is a vertical cross-sectional view on the line 2—2 of Fig. 1; Fig. 3 is a top plan view; Fig. 4 is a horizontal-sectional view 30 on the line 4—4 of Fig. 1; Fig. 5 is an enlarged horizontal sectional view through the front end of the gate showing a suitable latch for the gate.

My improved gate comprises a pair of L 35 angle iron bars forming, when placed together with their flanges parallel and projecting in the general plane of the gate toward the opposite end thereof, a latch bar 1, and a similar pair of L angle irons oppositely located and similarly placed and secured, forming a hinge bar 2, said latch and hinge bars forming the end uprights of the gate, and the separate L angle irons of each of said end uprights 1 and 2 are riveted or 40 otherwise fastened together and thus clamped upon the wire or other form of filler forming the body of the gate. When a wire filler is employed while the ends of the intervening wires are clamped between the 45 angle bars each alternate horizontal wire is twisted around the end bars as shown. The pairs of end bars 1 and 2 are connected together at their upper and lower ends by pairs of top and bottom horizontal bars 3 50 also formed of angle iron. The pairs of

bars 3 are spaced apart intermediate their ends by spacing blocks 4 and have their ends brought together and riveted, bolted or otherwise secured to the upper and lower ends of the end bars 1 and 2. By thus constructing the upper and lower pairs of horizontal bars 3 said bars form truss braces whereby the top and bottom of the gate are securely braced.

Arranged between the end bars and secured at their upper and lower ends to the upper and lower horizontal bars 3 are vertically disposed pairs of cross bars 5 said bars being preferably of channel iron construction. Secured at their ends to the end cross bars 1 and 2 are pairs of diagonal brace bars 6 arranged to cross at the center of the gate and are connected near the upper and lower ends of the end bars as shown. The diagonal bars 6 are preferably formed of angle 75 iron and are trussed in the same manner as the upper and lower horizontal bars 3. The bars 6 are also bolted to the cross bars 5 and are spaced apart by spacing blocks 7.

Secured to the hinge post 8 of the gate is 80 a vertical gate supporting shaft or pintle 9 to which the gate is slidably and hingedly connected by hinge members in the form of bands or clips 10 which are secured to the hinge bars 2 and loosely engage the pintle 85. 9. The gate is supported in hinged engagement with the pintle 9 by a supporting collar 11 which is adjustably secured to the pintle by a set screw 12 whereby the gate 90 may be operatively supported in a raised or lowered position.

In order to automatically fasten the gate when swung to a closed position any suitable latch mechanism may be used and as an instance I provide a latch comprising a pair 95 of clamp plates 13 having their inner edges bent outwardly at an angle and then inwardly to form hook shape clamping flanges 14 adapted to be clamped into adjustable engagement with the angle iron front bars 1 100 by a clamping bolt 15 thus permitting the latch plates to be adjusted to the proper position for engaging suitable pawls 16 which are pivotally connected near their upper ends to a supporting plate 17 secured to the 105 latch post of the gate.

When the latch plates are engaged with the pawls they are prevented from being disengaged therefrom by the lifting of the gate 110 or without again rocking the pawls, by a

right angular stop flange 21 formed on the upper end of the pawl supporting plate 17 as shown.

From the foregoing description, taken in connection with the accompanying drawings, the construction and operation of the invention will be readily understood without requiring a more extended explanation.

Various changes in the form, proportion and the minor details of construction may be resorted to without departing from the principle or sacrificing any of the advantages of this invention as defined in the appended claims.

Having thus described my invention what I claim is:

1. A gate comprising a hinge bar composed of a pair of L angle irons arranged with one flange of each parallel with one of the other angle bars, forming in effect a T bar in two parts, a hinge bar of a similar construction, a wire filler connecting the two end bars, a top bar comprising a pair of L angle irons arranged with a flange of each vertical and the other flange of each projecting horizontally outward, the ends being secured to the tops of the hinge and latch bars, a bottom bar of similar construction connected to the bottoms of the hinge and latch bars, strut bars separating the irons of the top and bottom bars and forming trusses thereof, channel irons in pairs secured between the irons of the top and bottom bars with their flanges outward further trussing the top and bottom bars, a pair of diagonal angle iron crossed brace bars on each side of the gate connected to the hinge and latch bars, and a strut bar between the brace bars at their crossings.

In testimony whereof I have hereunto set my hand in presence of two subscribing witnesses.

FRANCIES E. ELDREDGE.

Copies of this patent may be obtained for five cents each, by addressing the "Commissioner of Patents, Washington, D. C."

tom bars with their flanges outward further trussing the top and bottom bars.

2. A gate comprising a hinge bar composed of a pair of L angle irons arranged with one flange of each parallel with one of the other angle bars, forming in effect a T bar in two parts, a hinge bar of a similar construction, a wire filler connecting the two end bars, a top bar comprising a pair of L angle irons arranged with a flange of each vertical and the other flange of each projecting horizontally outward, the ends being secured to the tops of the hinge and latch bars, a bottom bar of similar construction connected to the bottoms of the hinge and latch bars, strut bars separating the irons of the top and bottom bars and forming trusses thereof, channel irons in pairs secured between the irons of the top and bottom bars with their flanges outward further trussing the top and bottom bars, a pair of diagonal angle iron crossed brace bars on each side of the gate connected to the hinge and latch bars, and a strut bar between the brace bars at their crossings.
